OUTER GARMENT

Abram K. Baer, Baltimore, Md., assignor to The
Strouse Baer Company, Baltimore, Md.

Application November 11, 1936, Serial No. 110,397

1 Claim. (Cl. 2—234)

This invention relates to an outer garment, more particularly to the short type of pants and has for its object to provide, in a manner as hereinafter set forth, a garment of the type referred to having its front formed in a manner to simulate a fly.

Further objects of the invention are to provide, in a manner as hereinafter set forth, a garment of the type referred to which is simple in its construction and arrangement, strong, durable, expeditiously positioned upon the wearer, pleasing in appearance and inexpensive to manufacture.

With the foregoing and other objects in view the invention consists of the novel construction, combination and arrangement of parts as will be more specifically described and which are illustrated in the accompanying drawing wherein is shown an embodiment of the invention, but it is to be understood that changes, variations and modifications may be resorted to which fall within the scope of the invention as claimed.

In the drawing:—

Figure 1 is a front elevation of a pair of short pants in accordance with this invention,

Figure 2 is a fragmentary view of the front of the garment illustrating the means providing for the simulation of the fly opened outwardly to illustrate a passage provided thereby,

Figure 3 is a fragmentary view in elevation looking towards the inner face of the front of the garment,

Figure 4 is a view similar to Figure 3 with the fly simulation means opened rearwardly to show the passage provided thereby, and

Figure 5 is a section on line 5—5, Figure 1.

The garment includes a body part 1 formed at the upper ends of its front and back spaced openings 2 and spaced external loops 3. A belt 4 slidably extends through the loops 3.

The body part 1 includes a front 5, a back 6, a crotch 7 and a pair of sides 8 having the upper portions thereof split. Reinforcing strips 9, 10 of strap-like form are secured to the inner faces 45 of the front and back 5, 6 respectively, at the upper ends of the latter. Extending from the body part 1 is a pair of short leg parts 11, 12.

The front 5 of body part 1 is formed of two sections 13, 14. The section 13 at its inner side 50 has extended therefrom a narrow flap 15 which is imperforated throughout arranged at the left of the crotch 7 and extends from the upper end of one of the sides of the crotch 7 at the front of the latter to the upper part of body part 1. The major portion 16 of flap 15 is of uniform

width throughout. The remaining portion 17 gradually decreases in width from its point of emergence with the portion 16. The latter has a straight edge 18. The portion 17 has a curved edge 19 which extends from the lower end of the edge 18 and merges at its lower end into the upper end of that side, as aforesaid of the crotch 7. The edges 18 and 19 are free. The section 14 at its inner side has extended therefrom a flap 20 of the same width, length and form as the flap 15. The portion of greater length and of uniform width of the flap 20 is indicated at 21. The remaining portion of the flap 20 is indicated at 22. The straight edge of portion 21 is designated 23 and the curved edge of portion 22 at 24. The flap 20 is folded against the inner face of section 14 in a manner to oppose the flap 15 whereby the edges 23 and 24 of the flap 20 will be flush with the edges 18 and 19 respectively of the flap 15. The bend provided by the flap 20 is indicated at 25. To the left of and in proximity to the bend 25 a row of stitching 26 is provided. The stitching 26 extends from the upper end of body part 1 to a point above and in proximity to the portions 17, 22 of the flaps 15 and 20. The row of stitching 26 connects the major portion of the length of the flaps 12 and 20 together. The portions of the flaps 15, 20 below the lower end of the stitching 26 coact to provide a passage 27. The row of stitching 26 provides the inner side of the section 14 with a vertically disposed expandable pleat 28 having its free edge, which is the bend 25, aligning with the upper end of the front of the side 29 of the crotch 7. The row of stitching 26 is substantially in alignment with the upper end of the front of the side 30 of the crotch 7. A row of stitching 31 is employed for securing the flap 20, in proximity to the edges 23, 24 of the flap against the inner face of the section 14. The row of stitching 31 extends from the upper end of flap 20 to the upper end of the front of side 30 of the crotch 7, and conforms in contour to the edges of flap 20. The row of stitching 31 is free of the flap 15. The edges 18 and 19 of the flap 15 and the edges 23 and 24 of the flap 20 are provided with a piping throughout as at 32. The upper end of the flap 15 extends between the strip 9 and the section 14. A means indicated at 33 is employed for securing the upper portions of the flaps 15, 20, the section 14 and the strip 9 together. A horizontally disposed means indicated at 34 is employed for securing the sections 13 and 14 together at the upper end of the front of the crotch 7.

What I claim is:—

In an outer garment, a body part including a front and a crotch, said front being formed of a pair of oppositely disposed sections having im-
5 perforate flaps of like form extended from their inner sides, said flaps having outer side edges formed with straight upper portions and inwardly curved lower portions, the flap of one of said sections being inwardly folded against the inner
10 face of the latter to oppose the other of said flaps whereby the flaps are concealed the outer face of the said front is provided with a bend aligning with the upper end of a side of the crotch at the front of the latter, the said non-
15 folded flap having its outer side edge merging into the upper end of the other side of the crotch at the front of the latter, said flaps, when op- posed, disposed in a like direction and extended laterally with respect to the said other side of
20 said crotch, said flaps extending from the upper end of the front of the crotch to the upper portions of said sections, a row of stitching ad- jacent said bend for connecting said flaps to-

gether, said row of stitching extending from the upper portion of the body part to a point re-
5 moved from the lower end of the flaps and in connection with a portion of the folded flap and a portion of the section having the folded flap providing the front of said body part with an expansive pleat aligning with the upper end of the front of the crotch, said row of stitching aligning substantially with the said other side of the crotch, the portions of said flaps below and 10 free of connection to said row of stitching co- acting to provide a horizontally disposed passage- way open at each end, a row of stitching co- extensive with the length of the folded flap, spaced from the said side edge of the latter 15 spaced from and of greater length than the other row of stitching and providing for securing said folded flap against the inner face of that section of which it forms a part and horizontally dis- posed means for securing said sections together 20 at the upper end of the front of the crotch.

ABRAM K. BAER.
